[57] CLAIM

The ornamental design for a christmas wreath shadow box, as shown and described.

DESCRIPTION

FIG. 1 is a front elevational view of a christmas wreath shadow box showing my new design;

FIG. 2 is a bottom plan view thereof, the top and adjacent sides being mirror images of that shown;

FIG. 3 is a rear elevational view thereof; and

FIG. 4 is a vertical cross-sectional view thereof, taken along line 4—4 of FIG. 1.

FIG-1

FIG-4
